ELECTRIC SWIVEL CONNECTER

Charles Henry Golden, Green Island, and John Baylus Smith, Troy, N. Y.

Application July 25, 1932. Serial No. 624,522

1 Claim. (Cl. 173—359)

The invention relates to a swivel and more especially to an electric swivel connector for conductor leads or wires.

The primary object of the invention is the provision of a connector of this character, wherein an electric cord as used with electric irons, curling irons, electric hand drills or other electric appliances will be prevented from twisting during the use of such appliances and thus obviating any interruption in the flow of electric current as well as avoiding damage to the leads or wires which ordinarily results from distortion, twist or bending of the leads or wires during use.

Another object of the invention is the provision of a connector of this character, wherein it is made of separable sections so that these sections may be detached from each other, the connector being of novel form to assure against interruption of electric current to the appliance during the use thereof and without the twisting of the leads or wires for current supply thereto.

A further object of the invention is the provision of a connector of this character, wherein a perfect swivel is had between the separable sections thereof, thereby permitting in its use the proper manipulation or handling of an electrical appliance without interruption of current or twist or undue distortion of the leads or wires delivering current thereto.

A still further object of the invention is the provision of a connector of this character which is comparatively simple in construction, thoroughly reliable and efficient, compact, strong, durable, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a side elevation of a connector constructed in accordance with the invention.

Figure 2 is a fragmental vertical sectional view through a connector constructed in accordance with the invention and taken approximately on the line 2—2 of Figure 1.

Figure 3 is a sectional view on the line 3—3 of Figure 2 looking in the direction of the arrows.

Figure 4 is a sectional view on the line 4—4 of Figure 2 looking in the direction of the arrows.

Figure 5 is a sectional view on the line 5—5 of Figure 2 looking in the direction of the arrows.

Figure 6 is a sectional view on the line 6—6 of Figure 2 looking in the direction of the arrows.

Figure 7 is a sectional view on the line 7—7 of Figure 2 looking in the direction of the arrows.

Similar reference characters indicate corresponding parts throughout the several views in the drawings.

Referring to the drawings in detail, the connector, in this instance, comprises the male and female sections 10 and 11 respectively of a housing or shell, the male member having a reduced inner end 12 for telescopic fitting within the rim 13 at the inner end of the female section 11, while externally of said male section contiguous to the reduced inner end 12 is an annular bead 13 with which are engageable hand releasable spring latches or catches 14, these being riveted or otherwise made fast externally to the rim 13 of the section 11 and in this manner these sections are detachably joined with each other.

The sections 10 and 11 are axially bored to provide the circular way or bore 15 centrally therethrough and loosely fitted in the bore or way 15 in both sections 10 and 11 are the tubular stems 16 and 17 respectively, the stem 16 being common to the section 10 and the stem 17 common to the section 11 while at the inner ends of said stems are heads 18, these and likewise the stems 16 and 17 being made from insulating material. One of the heads 18 is formed with the extensions or flanges 19 while the other head 18 is formed with an annular channel or groove 20 receiving said extensions 19 which are adapted to travel within the groove or channel 20 on the interfiting thereof and the heads 18 rotatably confined within the rim 13 of the section 11 when joined with the section 10. The sections 10 and 11 are made from insulating material.

Carried by the heads 18 at their faces confronting each other when confined within the rim 13 are circular inner and outer concentrically arranged spaced terminal contacts 21 and 22 respectively, the inner contacts 21 being centered with respect to the sections 10 and 11 while supported by one inner contact 21 and one outer contact 22 are the roller wipers 23 and 24, preferably there being two aligned roller wipers with the inner contact and three roller wipers with the outer contact, these traveling on the remaining inner and outer contacts, while trained through the stems 16 and 17 are the conductor wires 25, these being joined at their terminals with the said contacts 21 and 22 for a completion of an electric circuit through the connector with swivel action between the sections 10 and 11 thereof.

The heads 18 have anchored thereto backing plates or disks 26 against which play bearing balls 27, these being held in cages 28 built upon follower disks 29 within sockets 30 in the respective sections 10 and 11, while working against the follower disks 29 are coiled expansion springs 31, these being seated in the said sockets 30 and urge the disks 29 in the direction of the heads 18 with the balls 27 working upon the plates or disks 26 and in this fashion the heads 18 are yieldably forced toward each other for maintaining an electrical connection with the contacts 21 and 22 through the instrumentality of the wiper wheels 23 and 24 within the connector. It should be apparent that the heads 18 are free for independent relative rotation with respect to each other so that the wires or leads 25 cannot become twisted nor distorted and these wires or leads 25 are for use as an electric cord of electric appliances.

The stem 16, in this instance, is formed with an annular flange 32 having a knurled periphery 33 while the outer end of this stem is constructed to provide a screw attaching terminal 34 for a plug of the connector, the flange 32 with the knurled edge 33 being a hand turning medium for the engagement of the terminal 34 in an electric fixture socket. The terminal 34 is fitted with the center electric contact 35 and the screw thimble or sleeve contact 36, these being of conventional make-up.

It should be apparent that the connector is highly efficient and serviceable and is in its nature a swivel joint for obtaining a free swiveling action

with continuous electric conducting paths for the current and in the use the conductors, wires, leads or the like, there being but two shown yet a greater number may be employed with the connector, the same will be prevented from twisting or becoming entangled one with the other when they are used for supplying electric current to electrical appliances.

What is claimed is:

A connector of the character described comprising a sectional shell with the sections separably connected, a rim formed on one section, a reduced portion formed on the other section and telescoped in the rim, heads confined within the rim between the sections and rotatable relative to each other, stems on said heads and passed loosely through the sections exteriorly thereof and adapted to accommodate electric wires, contacts carried by the heads and having the wires connected therewith, resilient means within the sections and active upon the heads to move the same toward each other for the engagement of the contacts, wiper rollers acting between the contacts, backing plates on the heads, bearing rollers included in said means and working against the backing plates, a screw plug terminal on one of the stems, the wires in one stem being connected to the plug terminal and a knurled annular flange on the stem and next to the said screw terminal for permitting the turning of said stem for the detachable engagement of the screw terminal in an electric lamp socket.

CHARLES HENRY GOLDEN,
JOHN BAYLUS SMITH.
